WALTER L. DREYFUS, OF SAN FRANCISCO, CALIFORNIA.

AUTOMATIC CONTROLLING MECHANISM FOR OIL BURNERS.

Application filed December 8, 1924. Serial No. 754,553.

This invention relates to an automatic controlling mechanism for oil burners.

A considerable variety of oil burners are employed in conjunction with hot water heating systems, warm air furnaces and the like, for heating homes, office buildings, etc., and a number of attachments in the form of electric solenoids, thermostatic switches, etc., are used to automatically actuate the burners so that a uniform or predetermined temperature may be maintained.

The type of burner referred to in this application is that in which an atomizing cup is employed, which is either directly or indirectly rotated by means of an electric motor. A burner of this character must be provided with means for delivering oil to the atomizing cup, together with means for turning the oil off or on; it must be provided with means for opening or closing the motor circuit, and with means for igniting the oil and, in some instances, with means for pre-heating the atomizing cup when starting the burner. This involves the use of a number of electric switches and valves, together with means for automatically opening and closing the same, and while a number of automatic actuating mechanisms, such as previously referred to, are in more or less common use, satisfactory results are not obtained as they are too complicated and involved, or too delicate for dependable and continuous operation.

The object of the present invention is to provide an automatic actuated mechanism which is entirely mechanical in operation and rigid in construction; to provide a mechanism of this character which eliminates thermostats, solenoids and like delicate devices, and further, to provide a mechanical actuating mechanism which is adapted to be driven by the electric motor of the burner.

One form which my invention may assume is exemplified in the following description and illustrated in the accompanying drawings, in which—

Fig. 1 is a plan view of the burner actuating mechanism showing it in starting position.

Fig. 2 is a plan view with part of the mechanism removed for the purpose of illustrating the governor actuating portion of the mechanism.

Fig. 3 is a plan view similar to Fig. 1, but showing the mechanism in operation, said

view showing the gas valve in open position and the electric ignition circuit closed.

Fig. 4 is a view similar to Fig. 2 showing the governor in operating position.

Fig. 5 is a plan view similar to Fig. 1 showing the gas and oil valve in open position, the air damper in open position, and the ignition circuit broken.

Fig. 6 is a detail plan view showing the position assumed by the actuating mechanism when the burner is in operation.

Fig. 7 is a side elevation in section, taken on line 7—7 of Fig. 1.

Fig. 8 is a detail side elevation in section, taken on line 8—8 of Fig. 1.

Fig. 9 is a cross-section taken on line 9—9 of Fig. 1.

Fig. 10 is a plan view of a furnace showing an oil burner installed therein and the actuating mechanism connected therewith.

Referring to Fig. 10 of the drawings, it will be seen that the burner illustrated employs an atomizing cup A to which oil is delivered through a pipe 2, said cup serving the function of atomizing the oil by heat and centrifugal action and projecting the oil into the furnace chamber B, where combustion takes place. The atomizing cup is mounted on a vertically disposed shaft 3 and is rotated at a fairly high rate of speed by means of an impeller or turbine secured on the shaft at a point below the atomizing cup A, the turbine being in turn driven by a blast of air discharged from a blower C which is driven by an electric motor D.

To start a burner of this character it is first necessary to heat the atomizing cup by suitable means, as in this instance by a gas flame. To accomplish this preheating, a gas burner is placed below the atomizing cup and the cup is subjected to the heat of the flame and is thus preheated. It is necessary to provide a valve which will regulate the flow of gas to said burner; it is necessary to employ a pilot light or other means for igniting the burner; it is necessary to open an air damper E so that air in sufficient quantities will be delivered to start rotation of the atomizing cup after it has been preheated; it is necessary to turn on the oil after the cup has been preheated and has started rotating, and it is finally necessary to turn off the gas after the preheating has been accomplished and the oil ignited. All of these operations consist in the opening

and closing of electric switches, valves, air dampers, etc., and this is automatically taken care of by the actuating mechanism generally indicated at F. This mechanism is best illustrated in Figs. 1, 2, 7, 8 and 9, and particular reference will therefore be made to these figures.

By referring particularly to Figs. 1, 7 and 10, it will be noted that the actuating mechanism F, together with the motor D, is placed on a base plate 6. Mounted on the base plate is a frame 7 and disposed centrally of said frame is a stationary vertical shaft 8. Journalled exteriorly of the stationary shaft is a tubular shaft 9, which is rotated by means of a worm gear 10, this worm gear being driven by the electric motor D through a coupling 11 secured on a shaft 12. This shaft carries a worm pinion 13 which meshes with a worm gear 14. This gear is secured on a cross-shaft 15 and it in turn carries a worm pinion 16 which intermeshes with the worm gear 10. A reduction drive is in this manner obtained whereby the tubular shaft 9 is rotated at an approximate speed of one revolution in three minutes.

The motor D serves two main functions, first, that of driving the blower D, which is direct connected therewith, and secondly that of continuously rotating the tubular shaft 9 through means of the reduction worm gears just described. The motor circuit may be opened or closed by a manually actuated switch (not here shown) or through a thermostatically controlled switch located at any point desired.

The tubular shaft 9 carries a ratchet gear 17 on its upper end and it also carries a disk 18 which is loosely mounted thereon. A driving connection is, however, formed between the ratchet gear and the disk 18 through means of a pawl 19. This pawl is pivotally mounted as at 20 on the underside of the disk and it is adapted to be thrown into and out of engagement with the ratchet gear as will hereinafter be described. The pawl is thrown into engagement with the ratchet gear by means of a spring 21 and it is automatically thrown out of engagement with the ratchet gear when the disk has completed one revolution by means of a lever 22 and a detent wheel 23 with which it is adapted to engage. The detent wheel is provided with a number of interspaced teeth, as shown at 24, and it is automatically rotated the distance of one tooth when the burner is to be started. This rotation is transmitted to the detent wheel 23 through means of a fly ball governor generally indicated at G. This governor is mounted on the shaft 12 and is rotated at motor speed. Therefore, when the motor is started, governor G expands and as it is connected with a rocker arm 25, movement is imparted thereto in the direction of arrow a. The outer

end of the rocker arm is connected with a sliding bar 26 and mounted on the sliding bar is a pawl 27 which is adapted to engage with the teeth 24 of the detent wheel. Hence, when the governor expands and movement is imparted to the rocker arm 25 and the sliding bar 26, pawl 27 will engage one of the teeth of the detent wheel and impart a rotary motion thereto so as to advance the wheel $\frac{1}{10}$ of a revolution, as there are ten teeth on 75 the detent wheel. This advance moves one tooth of the detent wheel out of engagement with the arm 22 of pawl 19 and the pawl is thus released and is thrown into engagement with the ratchet gear 17 due to the action of 80 spring 21.

The tubular shaft 9, together with the ratchet gear, normally rotates in the direction of arrow b (see Fig. 1) and as the pawl 19 engages the ratchet gear and forms an interlock between the gear and the disk 18, rotary movement will be transmitted to the disk in the same direction. The disk will rotate one revolution and the pawl 19 will then be thrown out of engagement as 90 lever 22 will again engage with one of the teeth of the detent wheel, thus rocking it and throwing it out of engagement with the ratchet gear. The one revolution of the disk 18 takes place when the burner is started. It first of all closes an electric circuit through an electric ignition device; it secondly turns on the gas to the burner, whereby the atomizing cup is preheated; third, it opens the air damper E and almost simultaneously therewith opens the oil valve which regulates the flow of oil to the atomizing cup; fourth, it opens the circuit through the electric ignition device, and fifth, closes the valve which regulates the flow of gas to the preheating burner. These several operations are accomplished as follows:

Mounted on one side of the base is a pair of valves of any suitable construction which are generally indicated at 30 and 31. The lower valve regulates the flow of gas to the preheating burner and the upper valve controls the flow of oil to the atomizing cup. The valve 30 is provided with a stem 32 and the valve 31 with a stem 33. (See Fig. 9). Stem 32 is connected through means of a link 34 with a cam lever 35 pivotally mounted on the frame as at 36. The stem 33 of valve 31 is connected through means of a link 37 with a cam-actuated bell crank 38, which is also pivotally mounted on the frame as at 36. Hence, when a rocking movement is transmitted to the cam lever or the bell crank, movement is simultaneously transmitted to either open or close the connected valves 30 and 31. To transmit a rocking movement to the bell crank and the cam lever, a pair of pins 39 and 40 is employed. The normal position of the pins 39 and 40 when the disk 18 remains stationary, is 130

shown in Fig. 1 and their first actuating position, after disk 18 starts rotation, is shown in Fig. 3.

The ignition device may be of any suitable character; for instance, a coil of wire disposed in front of a pilot burner or any other suitable device. When an electric circuit is closed, so that current is permitted to flow through the coil, it rapidly heats to a point where it will ignite the gas discharging from the pilot burner, the pilot burner again serving the function of igniting the gas when the preheating burner is thrown into operation. A pilot burner normally burns at all times and it might, therefore, be thought that the electric ignition is unnecessary, but practical experience has shown that pilot lights blow out or become otherwise extinguished and it is for this reason that electric ignition is resorted to as a matter of protection, and it also happens that certain people object to the use of pilot lights and the electric ignition is then depended upon to ignite the gas discharging from the preheating burner. In any event the electric ignition is necessary and useful and it is in this instance controlled by an electric circuit generally indicated at H. (See Figs. 1 and 3.)

The switch is of any suitable construction and the circuit therethrough is opened and closed by means of a switch lever 41. Pin 40 assumes a position adjacent the switch lever when the disk is stationary and it therefore immediately engages the switch lever and throws it to closed position the moment the disk 18 starts rotation, the closed position of the switch being shown in Fig. 3. Therefore, if the pilot light should happen to be out, it can readily be seen that it will be instantly ignited. Pin 39 assumes a position just forward of the cam lever 35 when the disk stands stationary and it engages the cam point 35^a of lever 35 a moment after the circuit through the electric switch has been closed. The pin 39 swings the cam lever about its pivot 36 and thereby imparts a motion through the link 34 and the rod 32 to open the gas valve 30. The gas controlled by this valve flows to the preheating burner and it is there ignited either by the electric ignition device or the flame of the pilot burner.

By again referring to Figs. 1 and 3, it will be noted that the cam lever 35 is provided with a heel portion 35^b which is adapted to be engaged by a latching lever 42. This lever normally assumes the position shown in Fig. 3, where it engages a stop pin 44 and being held in engagement with this pin by means of a spring 45. Therefore, when the cam lever is rocked to the position shown in Fig. 3, the heel thereof engages the notch in the latching lever 42 and the gas valve 30 is thus held in open position while pin 39

continues to rotate with the disk. Pin 40 also moves away from the switch arm 41 and the circuit through the switch is thus automatically broken.

Pin 39 serves two functions, first, that of opening the gas valve, and secondly, that of closing the same. Pin 39 is shorter than pin 40 and therefore passes below the switch lever 41 and also the bell crank 38. Pin 40 is longer and it serves two functions, that of making and breaking a circuit through the electric switch, and that of opening the oil valve and also the air damper. By referring to Fig. 5 it will be noted that pin 40 has advanced to a position where it has engaged 70 the cam end 38^a of the bell crank 38. This engagement imparts a rocking movement to the bell crank 38 about its pivot 36 and this movement is transmitted through the link 37 and rod 33 to open the oil valve 31. The outer end of the bell crank is connected through a link 50 with the damper E and the air damper and the oil valve are therefore opened substantially at the same time, the arrangement being such that the air damper 75 is opened slightly in advance of the oil valve, the object being to permit the air to enter the burner so that it may start rotating the atomizing cup a moment prior to the admission of oil.

Pin 40 leaves the cam point 38^a during the rotation of the disk and means must, therefore, be provided for securing the bell crank in its rocked position. This is accomplished by providing a heel on the bell crank as indicated at 80 38^b. This heel engages the latching arm 51, which is also connected with a spring 45, and it is in this manner that the bell crank is locked when the air damper and oil valve have been 85 opened. It may here be stated that it remains in this position until the circuit through the motor is broken and the burner is stopped. The pin after leaving the cam point 38^a continues moving with the disk and it finally reaches its stop position at a point adjacent the switch lever 41, as shown in Fig. 6. At this point the driving connection between the disk and the ratchet gear is broken by 90 engagement of the latch arm 22 with the detent-wheel and the disk will therefore remain stopped until the motor is stopped and again started. The pin 39 reaches the position shown in Fig. 6 when the disk is stopped, but before it reaches this position it engages 95 the end of the latch arm 42 and rocks this a sufficient distance to release the heel 35^b of the cam lever 35. This when released is pulled back to normal position by means of a spring 55 and gas valve 30 is thus automatically closed a few seconds after the air damper has been opened and the oil valve turned on. In other words, the preheating burner continues burning until the oil has 100 been turned on and ignition of the oil is thus 105 110 115 120 125 130

insured, as the atomizing cup has been sufficiently heated to vaporize the oil and to project it by centrifugal action. The oil or gases thus projected are ignited by the pre-heating burner and as the preheating burner continues operation a few seconds after the oil is turned on, ignition of the oil is insured.

When the disk 18 has completed one revolution and the driving connection is broken, it can be seen that several operations have been performed. First, the pilot light has been ignited by the electric ignition; secondly, the valve 30 has been opened so as to supply gas to the preheating burner and this gas is ignited by the pilot burner; third, the air damper is opened when the atomizing disk has attained vaporizing temperature; fourth, the oil is turned on a moment after the atomizer has reached vaporizing temperature and has started rotation due to the admission of air, and fifth, the valve 30 is again closed a few seconds after the oil has been turned on. The motor will continue rotating as the circuit therethrough has not been affected and, in fact, it must continue rotating as long as the burner is to be operated as its main function is that of driving the blower which delivers the air to rotate the burner and to supply combustion. The governor G, together with the reduction gearing, the tubular shaft and the ratchet gear 17, will also continue rotating, but disk 18 will remain stationary, as the driving connection formed through means of the pawl 19 has been broken and it will remain stationary until the motor is stopped and again started. The bell crank 38 has, however, been locked in a position where it retains the oil valve and the air damper in an open position and means must therefore be provided for automatically releasing the same when the motor is brought to a stop, or, in other words, when it is desired to shut off the burner. This release of the bell crank 38 is taken care of by the governor G and is accomplished as follows:

The governor G assumes the expanded position shown in Fig. 4 as long as the motor is in operation and the rocker arm 25 similarly assumes the position shown in Fig. 4 as long as the governor is expanded. The moment, however, that the motor circuit is broken and shaft 12 comes to a stop, governor G gradually contracts due to the action of its spring and rocker arm 25 is thus gradually rocked in a direction opposite to arrow a until it assumes the full line position shown in Fig. 2. This movement of the rocker arm returns the slide bar 26 and the pawl 27 to a point where the pawl will engage the next tooth on the detent wheel, when the motor is again started. In other words, merely returning the pawl to another actuating position.

The return of the rocker arm 25 also accomplishes another function, to-wit, that of releasing the latching arm 51 and this is accomplished by attaching a pusher bar 60 to the rocker arm 25. The outer end of this pusher bar is provided with an upwardly projecting pin 61 which engages the latching arm 51, thus throwing it to the position shown in Fig. 1. The latching arm is thereby swung away from the heel 38^b of the bell crank 38, and it is returned to its normal inoperative position shown in Fig. 1 by means of a pull exerted by a spring 62. The return rocking movement of the bell crank 38 closes the oil valve and similarly the air damper and the burner is thus shut off, as neither air nor fuel is supplied thereto. The pilot light would naturally continue burning, but should it be blown out or otherwise extinguished, it is obvious that it would automatically ignite whenever the burner is started, as closing of the motor circuit will again start rotation of the disk 18 and actuation of the switch lever 41, etc.

Briefly from the foregoing it can be seen that all functions are mechanically actuated and that solenoids, thermostats and like actuating mechanism are entirely eliminated. The only thermostat which could possibly be used in conjunction with this mechanism would be one to automatically make or break the motor circuit, but as this is a common feature, specific illustration thereof is thought unnecessary, particularly in view of the fact that the motor circuit may be manually opened and closed if desired.

Two valves are required in the present instance, one to supply gas for the preheating burner and one to supply oil to the atomizing cup. These valves are automatically opened and closed and they are connected with a rigid mechanism which positively insures opening and closing of the same. The mechanism is also provided with one air damper and one electric switch. These are also automatically opened and closed by the same mechanism, so that dependable and reliable operation is always available.

It should furthermore be noted that a common motor is employed to drive the burner and the actuating mechanism. This is also an important feature, as many other automatic actuating mechanisms require a separate motor for this purpose, while the present mechanism employs one motor, thereby eliminating complicated wire systems, additional switches, etc.

While certain features of the present invention are more or less specifically illustrated, I wish it understood that various changes in form and proportion may be resorted to within the scope of the appended claims. I similarly wish it understood that the materials and finish of the several parts employed may be such as the experience and

judgment of the manufacturer may dictate or various uses may demand.

Having thus described my invention, what I claim and desire to secure by Letters Patent is—

1. In temperature producing and controlling mechanism, the combination with a liquid fuel burner of an atomizer therewith, a valve controlling the flow of fuel to the atomizer, an electric motor whereby the atomizer is operated, an air blower driven by the motor to deliver air to the atomizer, a damper regulating the flow of air to the atomizer and a mechanical controlling mechanism also operated by the motor whereby the air damper is first opened a predetermined time period after the motor is started and then the oil valve opened a predetermined period after the opening of the air valve, and said mechanical controlling mechanism also adapted to close both the air damper and the oil valve when the motor is stopped.

2. In temperature producing and controlling mechanisms, the combination of a liquid fuel burner, an atomizer therein, an electric ignition device cooperating with the atomizer, a valve controlling the flow of fuel to the atomizer, an electric motor whereby the atomizer is actuated, a blower driven by the motor to deliver air to the burner, a damper regulating the flow of air, a mechanical controlling mechanism driven by the motor, and means actuated by the controlling mechanism whereby, first, an electric circuit is closed through the ignition device; second, the air damper is opened; third, the oil valve is opened; fourth, electric circuit through the ignition device is broken, and said controlling mechanism also adapted to automatically close the air damper and the oil valve when the motor stops.

3. In temperature producing and controlling mechanisms, the combination with an electric fuel burner of an atomizer therein, a valve controlling the flow of fuel to the atomizer, an electric motor whereby the atomizer is actuated, a blower driven by the motor to deliver air to the atomizer, a damper regulating the flow of air, an electric igniting device co-operating with the atomizer, a switch controlling the circuit therethrough, a mechanical controlling mechanism driven by the motor, and means actuated by the controlling mechanism whereby, first, the switch is actuated to close an electric circuit through the ignition device; second, the air damper is opened; third, the oil valve is opened; fourth, the switch is actuated to break the circuit through the ignition device, and said controlling mechanism also adapted to automatically close the air damper and fuel valve when the motor stops.

4. In a temperature producing and con-

trolling mechanism, a liquid fuel burner, an atomizer in said burner, a valve controlling a flow of oil to the atomizer, an electric motor, an air blower driven thereby adapted to deliver air to the burner, a gas burner adapted to preheat the atomizer, a damper in the blower, a valve controlling the flow of gas to the preheating burner, an electric ignition device cooperating with said preheating gas burner to ignite the same, a mechanical controlling mechanism driven by the electric motor, and means actuated by the controlling mechanism whereby first an electric circuit is closed through the ignition device, secondly, the gas valve is opened, third, the air damper is opened, fourth the oil valve is opened, and fifth the electric circuit through the ignition device is broken, and sixth the gas valve is closed.

5. A mechanical controlling mechanism of the character described comprising an electric motor, a shaft driven thereby, a governor on said shaft, a sleeve shaft driven by the motor and adapted to be continuously rotated by the same, a disk loosely mounted on the shaft, means actuated by the governor whereby a driving connection is formed between the sleeve shaft and the disk, and other means for breaking said driving connection when the disk has completed one revolution.

6. A mechanical controlling mechanism of the character described comprising an electric motor, a shaft driven thereby, a governor on said shaft, a sleeve shaft driven by the motor and adapted to be continuously rotated by the same, a disk loosely mounted on the shaft, means actuated by the governor whereby a driving connection is formed between the sleeve shaft and the disk, other means for breaking said driving connection, an electric switch, and means actuated by the rotation of the disk for opening and closing said switch.

7. A mechanical controlling mechanism of the character described comprising an electric motor, a shaft driven thereby, a governor on said shaft, a sleeve shaft driven by the motor and adapted to be continuously rotated by the same, a disk loosely mounted on the shaft, means actuated by the governor whereby a driving connection is formed between the sleeve shaft and the disk, other means for breaking said driving connection, a pair of valves, means actuated by the rotation of the disk for opening and closing one valve and for opening the other valve, and means actuated by the governor for closing said other valve.

8. A mechanical controlling mechanism of the character described comprising an electric motor, a shaft driven thereby, a governor on said shaft, a sleeve shaft driven by the motor and adapted to be continuously rotated by the same, a disk loosely mounted

on the shaft, means actuated by the governor whereby a driving connection is formed between the sleeve shaft and the disk, other means for breaking said driving connection, 5 a pair of valves, means actuated by the rotation of the disk for opening and closing one valve and for opening the other valve, means actuated by the governor for closing said other valve, an electric switch, and 10 means actuated by the rotation of the disk for opening and closing said switch.

9. The combination with a liquid fuel burner having an atomizer, a preheating gas burner, a blower for delivering air thereto, 15 valve controlled pipe lines for delivering oil to the atomizer and gas to the burner, of an electric motor adapted to drive the blower and the atomizer, a mechanical controlling mechanism driven by the motor, and means 20 actuated by said controlling mechanism whereby, first, a valve is opened to deliver gas to the preheating burner, second, an air damper is opened to permit air to be delivered to the burner, third, an oil valve is 25 opened to deliver oil to the atomizer, and fourth, the gas valve is turned off.

10. The combination with a liquid fuel burner having an atomizer, a preheating gas burner, a blower for delivering air thereto, 30 valve controlled pipe lines for delivering oil to the atomizer and gas to the burner, of an electric motor adapted to drive the blower and the atomizer, a mechanical controlling mechanism driven by the motor, means actuated by said controlling mechanism whereby, first, a valve is opened to deliver gas to the preheating burner, secondly, an air damper is opened to permit air to be delivered to the burner, third, an oil valve is 35 opened to deliver oil to the atomizer, and fourth, the gas valve is turned off, a governor driven in unison with the mechanical controlling mechanism, and means actuated by said governor for closing the oil valve and 40 the damper when the motor is stopped.

11. The combination with a liquid fuel burner having an atomizer, a preheating gas burner, a blower for delivering air thereto, valve controlled pipe lines for delivering oil 45 to the atomizer and gas to the burner, of an electric motor adapted to drive the blower and the atomizer, a mechanical controlling mechanism driven by the motor, means actuated by said controlling mechanism whereby, first, a valve is opened to deliver gas to the preheating burner, secondly, an air damper is opened to permit air to be delivered to the burner, third, an oil valve is 50 opened to deliver oil to the atomizer, and fourth, the gas valve is turned off, a governor driven in unison with the mechanical controlling mechanism, means actuated by said governor for closing the oil valve and 55 the damper when the motor is stopped, and 60 means actuated by the mechanical control-

ling mechanism for igniting the gas when delivered to the preheating burner.

12. In a mechanical controlling mechanism of the character described, a frame, an electric motor mounted thereon, a shaft journaled in the frame and driven by the motor, a governor on said shaft, a reduction gear train driven by said shaft, a second shaft driven at reduced speed by said reduction gearing, a disk loosely mounted on said shaft, means actuated by the governor whereby a driving connection is formed between the second shaft and the disk, and other means for breaking the driving connection when the disk has completed one revolution. 70 75 80

13. In a mechanical controlling mechanism of the character described, a frame, an electric motor mounted thereon, a shaft journaled in the frame and driven by the motor, a governor on said shaft, a reduction gear train driven by said shaft, a second shaft driven at reduced speed by said reduction gearing, a disk loosely mounted on said shaft, means actuated by the governor whereby a driving connection is formed between the second shaft and the disk, other means for breaking the driving connection when the disk has completed one revolution, an oil and a gas regulating valve disposed adjacent the frame, an air damper, means actuated by rotation of the disk whereby the gas valve is opened and closed, means actuated by the rotation of the disk whereby the air damper and the oil valve are opened, and means actuated by the governor whereby the oil valve and air damper are closed. 90 95 100

14. In a mechanical controlling mechanism of the character described, a frame, an electric motor mounted thereon, a shaft journaled in the frame and driven by the motor, a governor on said shaft, a reduction gear train driven by said shaft, a second shaft driven at reduced speed by said reduction gearing, a disk loosely mounted on said shaft, means actuated by the governor whereby a driving connection is formed between the second shaft and the disk, other means for breaking the driving connection when the disk has completed one revolution, an electric switch, a gas valve, means actuated by the rotation of the disk whereby the circuit through the switch is opened and closed, and other means actuated by the rotation of the disk whereby the gas valve is opened and closed. 105 110 115 120

15. In a mechanical controlling mechanism of the character described, a frame, an electric motor mounted thereon, a shaft journaled in the frame and driven by the motor, a governor on said shaft, a reduction gear train driven by said shaft, a second shaft driven at reduced speed by said reduction gearing, a disk loosely mounted on said shaft, means actuated by the governor whereby a driving connection is formed between 125 130

the second shaft and the disk, other means for breaking the driving connection when the disk has completed one revolution, an electric switch, a gas regulating valve, an oil regulating valve and an air damper, means actuated by the rotation of the disk whereby the switch is opened and closed, means actuated by the rotation of the disk whereby the gas valve is opened and closed, means actuated by the rotation of the disk whereby the oil valve and air damper are opened, and means actuated by the governor for closing the oil valve and air damper.

WALTER L. DREYFUS.
